UNITED STATES PATENT OFFICE

165,029

SKIRT

John Stephen, Roslindale, Mass.

Application June 17, 1949, Serial No. 3,354

Term of patent 3½ years

(Cl. D3—26)

To all whom it may concern:

Be it known that I, John Stephen, a citizen of the United States, residing at 298 Cornell Street, Roslindale, State of Massachusetts, have invented a new, original, and ornamental Design for a Skirt, of which the following is a specification, reference being had to the accompanying drawing, forming a part hereof.

The back of the skirt which is not shown is conventionally plain and the essential features of the invention reside in the portion shown in full lines on the drawings.

I claim:

The ornamental design for a skirt, as shown and described.

JOHN STEPHEN.
